UNITED STATES PATENT OFFICE.

EDWARD BATTEN, OF KIRKCALDY, SCOTLAND.

MACHINERY FOR USE IN THE MANUFACTURE OF MOSAIC OR INLAID FLOOR-CLOTH.

SPECIFICATION forming part of Letters Patent No. 694,233, dated February 25, 1902.

Application filed July 29, 1901. Serial No. 70,154. (No model.)

To all whom it may concern:

Be it known that I, EDWARD BATTEN, a subject of the King of Great Britain, residing at Kirkcaldy, Scotland, have invented new and useful Improvements in Machinery for Use in the Manufacture of Mosaic or Inlaid Floor-Cloth, of which the following is a specification.

My invention relates to that type of machinery for use in the manufacture of mosaic or inlaid floor-cloth in which tesserae-cutting cylinders are arranged to deposit the cut tesserae upon a backing while the latter is engaged with a pin or card covered cylinder the pins or teeth of which project through the said backing and engage with the tesserae deposited on it and hold them in place thereon, the backing and tesserae afterward passing together to a heater and being subjected to pressure for the purpose of causing adhesion of the tesserae to each other and to the backing.

My said invention consists in the improvements in machinery of the said type, which are hereinafter described.

The objects of my said improvements are as follows: first, to admit of tesserae of a greater variety of colors being cut by the machinery and used in the production of the pattern without increase of the diameter of the pin-carrying cylinder upon which the inlaying or arrangement of the tesserae on the backing fabric takes place; further, to admit of increase of speed of the machinery without decrease of the time available for correction of the pattern by hand; further, to provide for removal from the heads of the cutter-cylinder plungers when projected from between the cutters of such of the tesserae as have not been transferred to or inlaid on the backing fabric by the action of the machinery and of such of the tesserae as are not required to make up the pattern, the removal of which tesserae in machines provided with additional cutting mechanism according to my said invention cannot be effected by the ordinary means.

I will describe my said invention with reference to the accompanying drawings.

Figure 1 represents diagrammatically in side view the principal of the working parts of

a machine of the aforesaid type having my said improvements combined therewith. Figs. 2 and 3 are enlarged sectional views of my arrangements for removal of tesserae from the heads of the cutter-cylinder plungers when projected from between the knives. Fig. 4 is a detail hereinafter referred to.

In the following description the parts of the said drawings are referred to by the letters marked thereon. The same letters of reference indicate the same parts in all the figures of the drawings. The arrows on the said figures indicate the direction of rotation of the parts.

a represents the pin-covered cylinder on which the inlaying is effected.

b' b² b³ b⁴ represent the ordinary tesserae-cutting cylinders, and *c' c² c³ c⁴* the ordinary pressing-cylinders against which the said cutter-cylinders act.

d represents the backing fabric, which is carried partly around the cylinder *a* and thence through and from the machine, as hereinafter described.

e represents the ordinary heated cylinder for producing adhesion of the tesserae to each other and to the backing fabric.

f is a drum, and *f'* are rollers supporting an endless sheet by which the mosaic or inlaid fabric, consisting of the backing fabric with the tesserae thereon, is carried around the heated cylinder *e*, as usual. *g g g g* are the ordinary pressing-rollers for pressing the said mosaic or inlaid fabric against the said cylinder *e*.

h h are rolls, and *i i* are scrapers bearing on the cylinder *e* and constituting the ordinary means for cleaning the said cylinder, and *j* is the ordinary wax-applying roll.

k l are two cylinders which I term, respectively, the "bending-cylinder" and the "justifying-cylinder," and the arrangement of which in the machine in the positions illustrated constitutes one of my aforesaid improvements. The surface of the said bending-cylinder *k* is plain and smooth or without any projections, and the surface of the justifying-cylinder has pointed pins projecting from it or is covered with card fabric. As shown in Fig. 1, the mosaic fabric on leaving the inlaying-cylinder *a* passes first under the

bending-cylinder *k* and then over the justifying-cylinder *l* on its way to the heated cylinder *e*. The bending-cylinder *k* rotates freely as the mosaic fabric passes under it, and the 5 justifying-cylinder *l* receives motion from the pin-cylinder *a* through the medium of a toothed wheel *l'*. The object of the said bending-cylinder *k* is primarily to provide for the mosaic fabric being carried over a sufficient 10 portion of the pin-covered inlaying-cylinder *a* to admit of arrangement in juxtaposition to the said cylinder of the additional cutting mechanism, hereinbefore referred to. The said cylinder *k*, however, also serves to press 15 the mosaic fabric against the justifying-cylinder *l* and cause the pins of that cylinder to pass through the backing fabric and enter the tesserae thereon, and so hold them in place while the mosaic fabric is passing to the heated cylinder *e*. While on the justifying-cylinder *l* a large portion of the pattern-face of the mosaic fabric is exposed to view for examination of the pattern and correction of any errors 20 by attendants, who stand on a platform (indicated by the line *m*) and whose duty is to place tesserae in any spaces which may be unoccupied in consequence of the tesserae which should have been placed therein by the inlaying action of the machine having accidentally 25 remained on the heads of the cutter-cylinder plungers.

In the working of machinery embodying my aforesaid improvements the cloth which is to form the backing of the mosaic fabric lies, as usual, next the face of the inlaying-cylinder *a*, the pins of which project through the said backing and receive the tesserae, which are cut and deposited on it by the ordinary action of the knives and mechanism 30 of the cutter-cylinders. In passing under the bending-cylinder *k* the backing is outermost, and in passing around the justifying-cylinder *l* the tesserae are outermost, so that the pattern-face of the fabric is then exposed and 35 accessible to the attendants standing on the platform *m*.

In consequence of the mosaic fabric being by means of the bending-cylinder *k* kept in contact with a larger portion of the cylinder 40 *a* than is possible in machines of the ordinary construction space is obtained for the arrangement in connection with the said cylinder *a* of more than the ordinary number of sets of cutting mechanism in conjunction 45 with an inlaying-cylinder *a* of the usual diameter, which number has not heretofore exceeded four, whereas by my arrangement two additional sets of tesserae-cutting mechanism, making in all six, may be arranged in conjunction with the said inlaying-cylinder, as illustrated in Fig. 1, in which figure the said two additional sets of cutting mechanism are shown on the left-hand side of the said cylinder *a*, the cutter-cylinders of the said two sets 50 being marked, respectively, *b*⁵ *b*⁶ and the pressing-cylinders thereof *c*⁵ *c*⁶.

In consequence of the extent of surface of

the mosaic fabric exposed to view on the justifying-cylinder *l* being much larger than that exposed to view in existing machines which 70 do not comprise such cylinder my improved machines may be driven at a much higher speed than is usual in the case of existing machines without abbreviation of the time during which the pattern is under examination 75 for correction by hand.

The arrangements for removal of tesserae not inlaid and those not required from the cylinders *b*⁵ *b*⁶ of the two additional groups of cutting mechanism are best shown in Figs. 2 80 and 3. They consist in the case of both groups of pin or card covered rollers *n n o o*, geared to the respective cutter-cylinders, which rollers have arranged in conjunction with them clearing-combs *p p q q*. The pin- 85 rollers *n n* come into action when the plungers of the cutter-cylinders are projected by the ordinary mechanism provided for admitting of lubrication of their heads, the tesserae being then impaled and removed from the 90 plunger-heads by the pins of the said rollers and afterward released from the said pins by the said combs *p p*, from which they pass onto bars *p' p'*, supporting the said combs, and collect there until removed by hand. In 95 working with machines provided with my improvements I dispense with the usual lubrication of the plunger-heads and knives and instead I lubricate the material from which the tesserae are cut. The tesserae impaled 100 and removed from the heads of the plungers of the cutter-cylinders *b*⁵ *b*⁶ by the pins of the said rollers *o o* are cleared from the said pins by the combs *q q*. In the case of the cylinder *b*⁵ the tesserae fall from the clearing- 105 comb *q* onto an endless traveling belt *r*, which passes over rollers *r' r'*, one of which is geared to the roller *o*, whereby the tesserae are carried to a conveyer-box *s*. In the case of the cylinder *b*⁶ the tesserae are removed from 110 the clearing-comb *q* and thrown into a conveyer-box *t* by a rotatory brush *u*, to which rapid motion is communicated from any convenient source. *u'* is a comb projecting in 115 the path of motion of the outer part of the brush *u*, the purpose of which is to clear tesserae from the said brush.

To prevent "wandering" of the belt *r*, I prefer to connect it at its edges to pitch-chains engaged with sprocket-wheels on the necks 120 of its rollers *r' r'*, as illustrated in plan view in Fig. 4, in which figure the chain shown is marked *v* and the sprocket-wheels over which it passes are marked *v' v'*.

The construction I prefer for the combs *p p* 125 *q q* is that plainly illustrated in Figs. 2 and 3, in which figures the teeth of the said combs are shown as formed of wires secured at one end in and projecting from a plate.

The arrangements hereinbefore described 130 for removal of tesserae from the cutter-cylinders are supported by the parts of the frame of the machine in which the groups of cutting mechanism to which they are applied

are mounted. In Fig. 2 portions of the supports of the groups of mechanism containing the cutter-cylinders b^4 b^5 are shown at $w w$.

Although the pin-roller and comb arrangement hereinbefore described for removal of tesserae from the cutter-cylinders is especially designed for use in connection with the two additional groups of cutting mechanism in consequence of the means ordinarily used for that purpose not being available for use in connection with the said groups of cutting mechanism, yet the said arrangement is capable of use in connection with the other groups of cutting mechanism, and I prefer so to use it, and in Fig. 1 I have shown it as applied to them.

I am aware that it has been proposed to use hooked or curved pickers for extracting the tesserae not required for the pattern from the spaces between the tesserae-cutting knives and to arrange combs in conjunction with such pickers for detaching the tesserae therefrom, and in reference to such proposed use I would observe that such pickers were found to be unsuitable for use where the size of the tesserae was less than about one inch and a half square or in the case of tesserae of the form of right-angled triangles where the sides containing the right angle were each less than about one inch and three-quarters long, and, further, that the said pickers were not used and were not suitable for use for removing tesserae from the plunger-plates when the machine was so arranged that the said plunger-plates were projected out of the spaces between the knives by the action of the machine, but were designed and used solely for extracting the tesserae from out of those spaces. I refer to such use of pickers and combs in order that the distinction between them and my arrangement of pin-rollers and combs for removal of tesserae from the cutter-cylinders may be clearly perceived, the points of distinction being, first, that the pins of my pin-rollers are not curved or hooked, but are straight-pointed, and, further, that they do not act by tearing the tesserae out from the spaces between the knives, but by impaling the tesserae while they are held above the knives by the heads of the projected plungers. In consequence of these differences my pin-rollers are suitable for removing the smallest tesserae, the size of which is not more than one-quarter of an inch square.

I claim as my aforesaid invention of improvements in machinery for use in the manufacture of mosaic or inlaid floor-cloth and desire to secure by Letters Patent of the United

States of America—

1. In machinery for use in the manufacture of mosaic or inlaid floor-cloth the improvements hereinbefore described whereby the production of patterns containing a greater number of colors can be obtained without increasing the diameter of the pin-cylinder upon which the inlaying of the tesserae is obtained,

the said improvements consisting in the combination with the said pin-cylinder and a heating-cylinder, of a bending-cylinder around which passes the mosaic fabric on leaving the pin-cylinder, a pin-carrying cylinder on the pins of which the said fabric is pressed by the bending-cylinder and partly around which the fabric passes with the pattern-face outermost, so as to permit of correction of the pattern of the fabric while it is so passing, cutter-cylinders and pin-rollers and combs arranged relatively to the cutter-cylinders and adapted for the removal of the tesserae from the heads of the plungers of the cutter-cylinders when projected from the knives thereof.

2. In machinery of the character described, a bending-cylinder around which passes the fabric, and a justifying-cylinder arranged in suitable relation to the bending-cylinder.

3. The means hereinbefore described and illustrated in the accompanying drawings for removal of tesserae from the plunger-heads of the cutter-cylinders when the plungers are projected from between the knives by the action of the cylinder mechanism that is to say the arrangement contiguously to the said cylinders of rotatory rollers from the peripheries of which project straight-pointed wires or pins adapted to penetrate the said tesserae and remove them from the plunger-heads and the combination with the said rollers of combs for disengaging the tesserae from the said pointed wires or pins the arrangement of the said combs being such that the free ends of their teeth lie between the rows of pointed wires or pins on the said rollers and are in proximity to or in contact with the peripheries thereof.

4. In machinery of the character described, means for removal of tesserae from the plunger-heads of the cutter-cylinders when the plungers are projected from between the knives by the action of the cylinder mechanism that is to say, the arrangement contiguous to the said cylinders of rotatory rollers from the peripheries of which project straight-pointed wires or pins adapted to penetrate the said tesserae and remove them from the plunger-heads and the combination with the said rollers of combs for disengaging the tesserae from the said pointed wires or pins, the arrangement of the said combs being such that the free ends of their teeth lie between the rows of pointed wires or pins on the said rollers and are in proximity to or in contact with the peripheries thereof, and an endless traveling apron for receiving and carrying away the tesserae disengaged from the pin-roller by the combs.

5. In machinery of the character described, means for removal of tesserae from the plunger-heads of the cutter-cylinders when the plungers are projected from between the knives by the action of the cylinder mechanism that is to say, the arrangement contiguously to the said cylinders of rotatory rollers from the peripheries of which project straight-

pointed wires or pins adapted to penetrate the said tesseræ and remove them from the plunger-heads and the combination with the said rollers of combs for disengaging the tesseræ from the said pointed wires or pins, the arrangement of the said combs being such that the free ends of their teeth lie between the rows of pointed wires or pins on the said

rollers and are in proximity to or in contact with the peripheries thereof, and a rotatory brush for removing the tesseræ from the said comb.

EDWARD BATTEN. [L. S.]
